Des. 236,631
Patented Sept. 2, 1975

236,631

HOLDER FOR AN OPTIC FIBER ORNAMENT

Joseph M. Ahroni, P.O. Box 3907,
Seattle, Wash. 98124

Filed Apr. 25, 1974, Ser. No. 464,251

Term of patent 14 years

Int. Cl. D11—02

U.S. Cl. D29—1 B

FIG. 1

FIG. 2

FIG. 3

FIG. 4

FIG. 5

FIG. 6

FIG. 1 is a bottom plan view of a holder for an optic fiber ornament showing my new design;

FIG. 2 is a top plan view thereof;

FIG. 3 is a left side elevational view thereof;

FIG. 4 is a front elevational view thereof;

FIG. 5 is a rear elevational view thereof; and

FIG. 6 is an enlarged front perspective view thereof.

I claim:

The ornamental design for a holder for an optic fiber ornament, as shown and described.
